UNITED STATES PATENT OFFICE.

EDMUND BRUDER, OF CHICAGO, ILLINOIS, ASSIGNOR TO HAROLD I. KOPPELMAN, OF WILMETTE, ILLINOIS.

DISPENSER.

1,415,218.

Specification of Letters Patent. Patented May 9, 1922.

Application filed February 14, 1918. Serial No. 217,054.

To all whom it may concern:

Be it known that I, EDMUND BRUDER, a citizen of the United States, residing at Chicago, in the county of Cook and State of Illinois, have invented certain new and useful Improvements in Dispensers, of which the following is a specification.

This invention relates to improvements in devices for dispensing plastic substances, as, for example, grit soap, soap paste and the like.

In the accompanying drawings, Figure 1 is a side elevation of a dispenser embodying the features of my invention. Fig. 2 is a vertical sectional view taken in the plane of dotted line 2 of Fig. 1. Fig. 3 is a top plan view. Fig. 4 is a sectional view taken approximately in the plane of dotted line 4-4 of Fig. 2. Fig. 5 is a section on line 5-5 of Fig. 2. Fig. 6 is a section on line 6-6 of Fig. 2. Fig. 7 is a section on line 6-6 of Fig. 2, but looking upward. Fig. 8 is a fragmental vertical sectional view. Fig. 9 is a view illustrating a lock for the casing. Fig. 10 is a lower side view of a disk comprised in the dispenser. Fig. 11 is a top plan view of a container adapted for use with the dispenser.

While the dispenser may be located and supported in any suitable way, it is herein shown as comprising a bracket adapted to be attached to the wall. A bracket of any preferred form and construction may be employed. The one herein shown comprises a base 1 formed integral with a frame that supports the container and the extruding mechanism. The frame consists of a rear post 2 and a front post 3, the upper ends of said posts being connected by a disk 4, and the lower ends thereof being united by a disk 5.

The soap or other material to be dispensed is contained in a can 6, the body of which is cylindrical. The lower end of the can has a discharge opening of any desired form; herein is shown an elongated opening 7 (Fig. 11). At the upper end of the can is an inwardly extending annular flange 8 (Figs. 2 and 11). Within the can is a floating head 9 having an annular guide flange 10 that slides in contact with the cylindrical wall of the can. The can is supported within a casing 11 carried by the before-mentioned frame. The means for forcing the head 9 downwardly to extrude the soap through the outlet 7 includes

an internally-threaded sleeve 12. Said casing and sleeve are rigidly connected together and are severed to form two vertical halves which are pivoted to the frame so that they may be swung apart to permit the insertion and removal of cans and the restoration of the extruding mechanism to initial position. As best shown in Figs. 1 and 3, the two halves or sections are pivoted upon a pintle 13 fixed in the frame, and the two sections of the casing, being rigid with the sleeve sections, swing therewith. To permit of the relative swinging movement of the casing sections, they are cut away at their adjoining rear edges (Fig. 3). The sections may be locked in closed position by any suitable means, as, for example, a hook 14 pivoted at 15 on one section of the sleeve 12 and engaging a stud 16 on the other section. A coiled expansion spring 17 normally holds the hook 14 against a stop lug 18. The free end of the hook is beveled so as to be raised by the stud 16 when the sections of the sleeve are swung together. 19 is a housing, formed one-half on each section of the sleeve 12, for enclosing the lock. The hook may be pushed up out of engagement with the stud 16 by means of an implement inserted through a hole 20 in the bottom wall of the housing.

Each section of the casing 11 comprises an inwardly extending flange or ledge 21 (Fig. 2) on which the can 6 rests. As shown in Figs. 1 and 2, the casing 11 is provided with openings 22 through which labels or the like on the can may be seen. In order to prevent the can from being inserted into the casing in such position that the labels do not register with said openings, I place two pins 23 (Fig. 10) upon the lower side of the disk 5, which pins are not diametrically opposite each other. In the flange 8 of the can are formed two openings 24 (Fig. 11) to receive the pins 23.

The means for forcing the head 9 downwardly within the can comprises a plunger consisting of a disk 25 bearing against the head 9 and rigidly secured to a tubular stem 26. Said stem is slidable through an opening 27 in the head 5. The upper end of the stem 26 is connected to a member having a screw-thread connection with the sleeve 12. The upper portion of the stem 26 is rigidly secured to a disk 28 having a loose connection with an externally-threaded member 29

that engages the internally-threaded sleeve 12. Separating movement of the disk 28 from the member 29 is limited by an out-turned flange 30 on the upper end of the 5 stem 26, said stem extending slidably through a central opening in the member 29. The loose connection between the disk 28 and the member 29 consists of a lug 31 on the upper side of the disk 28, which lug 10 lies within an elongated recess 32 in the lower side of the member 29. When the member 29 is turned in the direction to cause said member to move downwardly in the sleeve 12, the end wall 33 of the recess 32 15 engages the lug 31 and causes the disk 28 also to turn.

The contents of the can being slightly compressible and expansible, extrusion of the soap would continue for a few moments 20 after downward movement of the member 29 had ceased, if means were not provided to prevent such action. For this purpose, I have provided a plurality of balls 34 (Fig. 6) lying in sockets 35 in the lower side of 25 the member 29 and in recesses 36 in the upper side of the disk 28. The recesses 36 are deeper at one end than at the other, so that as the balls 34 roll up the sloping bottom walls of said recesses, the disk 28 is 30 forced away from the member 29. Contact between the lug 31 and the end wall 33 of the recess 32 limits relative turning movement of the parts 28 and 29. When downward movement of the member 29 stops, expansion of the contents of the can causes the disk 28 to turn in the direction to bring the deep end of the recesses 36 into register with the balls 34, thus causing the disk 28 to approach the member 29. The pressure of the 40 soap thus expends itself in moving the disk 28 instead of in forcing soap through the outlet 7.

The means for rotating the member 29 comprises a finger lever 37 fixed upon a shaft 45 38 which is rotatably mounted in the disk 4. The lever 37 extends through a slot 39 in the enlarged upper end of the sleeve 12. A coiled tension spring 40 secured at one end to the frame and at its other end to an arm 50 of the lever 37 normally holds said lever against an end wall of the slot 39.

The shaft 38 is square in cross-section throughout most of its length. It extends into the tubular stem 26, being cylindrical at 55 its lower end to keep it central in the stem.

Within the member 29 is rotatably mounted a pawl-carrier 41 having, in this instance, the form of a disk. Said disk has a square central opening through which the shaft 38 60 extends slidably, whereby the disk is caused to turn with the shaft. 42 is a circular cover plate secured to the member 29 and overlying the disk 41. Said disk carries a suitable number of pawls 43 which are slidably 65 mounted in guideways in the disk. Expan-

sion springs 44 hold the teeth of the pawls against an annular series of interval ratchet teeth 45 formed in the member 29.

In use, the operator reciprocates the lever 37 one or more times, thus turning the 70 square shaft 38 and the pawl-carrier 41, the pawls 43 causing the member 29 to turn in the direction to travel downwardly in the sleeve 12. As the member 29 turns, the balls 34, acting against the sloping walls 75 of the recesses 36, crowd the disk 28 down until the end wall 33 of the recess 32 strikes the lug 31, after which further rotation of the member 29 causes the disk 28 to turn. The downward movement of the parts 28 80 and 29 causes the head 9 to descend in the can, whereby soap is forced out of the opening 7. When the operator ceases operation of the lever 37, the pressure of the sloping bottom walls of the recesses 36 against the 85 balls 34, due to the pressure of the contents of the can, causes the disk 28 to turn to bring the deepest portions of said recesses into register with the balls, in which movement the disk 28 approaches the member 29. The pressure on the contents of the can is thus relieved, and the flow of soap through the opening 7 ceases.

When the can 6 is empty, the casing 11 and sleeve 12 are opened, thus disengaging the sleeve from the member 29. The operator may then grasp the member 29 and raise it and the disk 25 until the container 6 can be slid off the ledges 21. A fresh can is then set in place, with the disk 25 resting 100 upon the head 9 of such can, and the casing 11 and sleeve 12 closed.

It will be understood that the invention is not limited to the particular construction herein disclosed, as various modifications 105 may be resorted to within the scope of the appended claims.

I claim as my invention:

1. A dispenser having, in combination, a container provided with an outlet, a plunger 110 for forcing the contents of the can through the outlet, an externally-threaded member connected to the plunger, an internally-threaded sleeve stationary relative to the container and containing said member, the 115 plunger extending axially of the sleeve, a pawl carrier rotatably mounted in said member, a pawl on the pawl carrier, said member having ratchet teeth which are engaged by the pawl, a shaft extending slidably 120 through the pawl carrier and axially of the plunger, said pawl carrier being rotatable with the shaft, and means for turning the shaft, said sleeve being formed of two pivoted sections adapted to be swung out 125 of engagement with said member.

2. A dispenser having, in combination, a container provided with an outlet, a plunger for forcing the contents of the can through the outlet, an externally-threaded member 130

connected to the plunger, an internally-threaded sleeve stationary relative to the container and containing said member, a pawl carrier rotatably mounted in said member, a pawl on the pawl carrier, said member having ratchet teeth which are engaged by the pawl, a shaft extending slidably through the pawl carrier and axially of the plunger, said pawl carrier being rotatable with the shaft, and means for turning the shaft.

3. A dispenser having, in combination, a container provided with an outlet, a plunger for forcing the contents of the can through the outlet, a threaded member connected to the plunger, a threaded part stationary relative to the container and coacting with said member, a pawl carrier rotatably carried by said member, a pawl on the pawl carrier, said member having ratchet teeth which are engaged by the pawl, a shaft extending slidably through the pawl carrier and axially of the plunger, said pawl carrier being rotatable with the shaft, and means for turning the shaft.

4. A dispenser having, in combination, a container provided with an outlet, a plunger for forcing the contents of the can through the outlet, a threaded member connected to the plunger, a threaded part stationary relative to the container and coacting with said member, the plunger extending axially of said part, a pawl carrier rotatably carried by said member, a pawl on the pawl carrier, said member having ratchet teeth which are engaged by the pawl, a shaft extending slidably through the pawl carrier and axially of the plunger, said pawl carrier being rotatable with the shaft, and means for turning the shaft.

5. A dispenser having, in combination, an extruding plunger having a tubular stem, an externally-threaded member connected to the stem, an internally-threaded sleeve containing said member, the plunger extending axially of the sleeve, a pawl carrier rotatably mounted in said member, a pawl on the pawl carrier, said member having ratchet teeth which are engaged by the pawl, a shaft extending slidably through the pawl carrier and axially of the plunger, said pawl carrier being rotatable with the shaft, and means for turning the shaft.

6. A dispenser having, in combination, a supporting frame, a casing comprising two sections pivoted to said frame, a can adapted to be supported within said casing, means for holding the sections in closed position, said can having an outlet, a plunger for forcing the contents of the can through said outlet, an externally screw-threaded member connected to the plunger, an internally-threaded sleeve containing said member, said sleeve consisting of two sections each rigidly connected to one of the

casing sections, and means for rotating said member.

7. A dispenser having, in combination, a supporting frame, a casing comprising two sections pivoted to said frame, a can adapted to be supported within said casing, said can having an outlet, a plunger for forcing the contents of the can through said outlet, an externally screw-threaded member connected to the plunger, an internally-threaded sleeve containing said member, said sleeve consisting of two sections rigid with the casing sections, and means for rotating said member.

8. A dispenser having, in combination, a plunger, a disk fixed to the plunger, an externally-threaded member axially alined with said disk, a ball lying in recesses formed in said member and disk, one of said recesses having a sloping wall, means to limit relative turning movement between the disk and the member, an internally-threaded part containing said member, and means for rotating said member in said part.

9. A dispenser having, in combination, a plunger, a disk fixed to the plunger, a threaded member axially alined with said disk, a ball lying in recesses formed in said member and disk, one of said recesses having a sloping wall, means to limit relative turning movement between the disk and the member, a threaded part coacting with said member, and means for rotating one of said threaded elements to move the plunger.

10. A dispenser having, in combination, a supporting frame, a casing comprising two sections pivoted to said frame, each of said sections having a ledge, a can adapted to be placed within said casing and rest upon said ledges, means for holding the sections in closed position, said can having an outlet, and means carried by said frame for forcing the contents of the can through said outlet.

11. A dispenser having, in combination, a supporting frame, a casing comprising two sections, one of which is movably connected to said frame, a can adapted to be supported within said casing, means for holding the movable section in closed position, said can having an outlet, and means carried by said frame for forcing the contents of the can through said outlet.

12. A dispenser having, in combination, a supporting frame, a casing comprising two sections pivoted to said frame, each of said sections having a ledge, a can adapted to rest upon said ledges, means for locking the sections in closed position, said can having an outlet, and means for forcing the contents of the can through said outlet.

13. A dispenser having, in combination, a container provided with an outlet, a plunger for forcing the contents of the can

through the outlet, an externally-threaded member connected to the plunger, an internally-threaded sleeve stationary relative to the container and containing said member, and means for rotating said member, said sleeve being formed of two pivoted sections adapted to be swung apart out of engagement with said member.

14. A dispenser having, in combination, a container provided with an outlet, a plunger for forcing the contents of the can through the outlet, an externally-threaded member connected to the plunger, an internally-threaded sleeve stationary relative to the container and containing said member, and means for rotating said member, said sleeve including a section adapted to be moved out of engagement with said member.

15. A dispenser for soap or the like, comprising, in combination, a pivotal support,

a casing comprising an upper portion and a lower portion, the upper portion being of less diameter than the lower portion and both of said portions being divided on a substantially vertical axis into two substantially equal halves, means for pivotally mounting the halves of the upper portion upon said pivotal support, the halves of the lower portion being carried by the corresponding halves of the upper portion, a container for soap to be dispensed adapted to be supported in the lower portion, said container having a discharge outlet in its lower end, and means including mechanism enclosed within the upper portion for forcing the contents of the container through said outlet.

In testimony whereof, I have hereunto set my hand.

EDMUND BRUDER.
